TRAIN PARALLAX COMPUTER

Frank L. Hereford, Jr., Swarthmore, Pa., and
Walter D. Whitehead, Jr., Old Church, Va., as-
signors to United States of America as repre-
sented by the Secretary of the Navy

Application April 27, 1948, Serial No. 23,475

1 Claim. (Cl. 235—61.5)

1
The present invention relates to train parallax correctors.

More particularly, it relates to apparatus which determines and transmits to a gun the angular correction in train due to parallactic error introduced by the distance between the gun and its director.

An object of the invention is to eliminate the train parallax error, that otherwise would exist, when a gun and its director are not at substantially the same point, by introducing the necessary correction for parallax into the gun signal.

The object of a modified form of the invention, also disclosed herein, is to correct for the future range of the target, instead of the range at the time of firing, by introducing a proper train parallax correction.

All these problems are solved automatically by the train parallax corrector, which not only computes the proper angular correction, but also automatically adds it to the gun orders.

It is easy to see that this correction for train parallax will increase directly as the separation of the gun from its director, but will decrease, inversely, with the range, that is, it will become smaller for a more distant target, as long as the range is large compared to said separation. It can also be shown that the train parallactic error increases with the train angle, and increases also with increasing elevation angle. The relation is expressed mathematically in the following paragraph:

When the base line between gun and director has the length b , in yards, and θg designates elevation angles and ϕg train angles, of the gun, the latter being measured in a clockwise direction, when seen from above, zero train angle in the case of a ship being the forward direction along the fore-and-aft line of the ship, the correction is given, in degrees, by the equation:

$$p_g = \frac{57.3b \sin \phi g}{R \cos \theta g}$$

for any range R . When a definite base line is assumed, say 100 yards, 57.3b becomes 5730.

The present error computer assumes that voltages proportional respectively to $\sin \phi g$ and $\cos \theta g$, and rotary motion (inversely) proportional to the range R , are available.

A clear understanding of the invention may be obtained from the present description and the accompanying drawings illustrating two specific embodiments thereof. In said drawings:

Figure 1 is a block diagram of the apparatuses and circuits;

2

Figure 2 is a circuit diagram of an amplifier that forms a part of the device; and

Figure 3 is a block diagram, similar in general to Figure 1, but showing a modified form.

5 The present invention provides an automatic means for correcting the error due to train parallax, existing whenever there is a distance between the gun director and the gun controlled and which will be serious whenever the director and the gun are at widely separated locations on a vessel.

In connection with the aiming or "pointing" of guns, it is customary to use devices known as computers, which are electrically operated devices for deriving voltages that represent the angles ϕg in train, and θg in elevation, of the gun, in terms of certain of their trigonometric functions, conveniently the sine of ϕg , and cosine of θg . These computers are well known in the art, and in and of themselves constitute no novel features. Hence their mechanical and electrical structures are not discussed herein, and mere block diagrams are employed instead.

Another apparatus used in pointing a gun is known as a "wind box" and has the purpose of correcting the data obtained from the computers, to allow for the deflecting effect, on the projectile, of the natural wind, and/or the relative motion of the ship carrying the gun, with respect to the air. This device is likewise well known and will be indicated here merely by a block diagram, marked "source of $\cos \theta g$," which is the measure of one of the voltage-outputs it yields.

A third auxiliary apparatus found in gun director installations is the "range-repeater," which includes a dial mounted on a shaft that rotates whenever the range of the target is changing, and is controlled electrically to keep in synchronism with a manually-rotated shaft of a radar range-finding apparatus. This range-repeater shaft is also employed in connection with the present invention and is likewise shown merely as a block diagram, suitably labeled.

Referring first to Figure 1, there is shown an input circuit 1, 2 to which is supplied a voltage proportional to $R \cos \theta g$. This voltage, as already explained, is here obtained from the voltage representing $\cos \theta g$ yielded by the wind box, by feeding this voltage across a 1,000 ohm potentiometer, not shown, the movable element of which is operated by the "present range" shaft in the range repeater box. A potentiometer 3, 26 having a resistance of the order of 50,000 ohms, is bridged across the wires 1 and 2, as is also a circuit consisting of the resistors 4 and 5 in series,

each of about 50,000 ohms, to the junction of which is connected the wire 6, which is thus a center tap, the potential of which corresponds to that of the mid-point of potentiometer resistor 3.

A voltage proportional to $\sin \phi g$ is obtained from the computer, as already stated, and is fed to the wires 6a and 7. A series resistor 8, of 5,000 ohms, is placed in one of these leads and a 2,000 ohm potentiometer 9, 10 is bridged across them as shown. The slider 10, connected to wire 11, bears on the potentiometer resistor 9 and is brought to such position of adjustment that the voltage between wire 6 and wire 11 represents $\sin \phi g$.

The amplifier 13 has a power supply 14 energized from the mains as shown. This amplifier supplies one phase of a two-phase alternating current motor 17 through the output leads 15 and 16 of said amplifier. The other phase of the motor 17 is supplied with properly phased alternating current at a suitable voltage, say 20 volts, derived from the mains and transformed in voltage and adjusted in phase angle by the phase network 18 which has the output leads 19 and 20. The details of a suitable amplifier are disclosed in Figure 2.

The motor 17 will run in one direction or the other, as determined by the lag or lead of the amplifier output with respect to the output from the network 18. The shaft 21 of the motor 17 operates the generator 22 directly, and through the gear box 23 and shaft 25 also operates the synchro-generator 24 and the arm 26 of the potentiometer 3. The motor 17 thus adjusts the potentiometer 3 into balance, by reducing the input to the amplifier 13 to zero. The generator 22, which has an exciting winding energized by leads 1 and 2, through a suitable resistor 77, prevents hunting by opposing the necessary small signal to the amplifier input to prevent overrunning of the motor 17. This signal is thus proportional to the voltage across leads 1 and 2 multiplied by the speed of shaft 21 of motor 17.

The synchro-generator 24 derives its field excitation from the alternating current mains, as indicated on the drawing, and yields an output through the set of three leads, marked 12 p_ϕ , which is fed to the gun director, not shown. This is the final output of the present device.

The amplifier, which is designated as a whole by reference character 13 in Figure 1, is shown in detail in Figure 2. It comprises four thermionic tubes, arranged in three stages. The first two tubes, 30 and 31, may suitably be twin triodes, such as type 6SC7. The final or power output stage includes preferably two beam-power tubes 32 and 33 connected in push-pull. Type 6V6 is indicated on the drawings as suitable.

The input to the amplifier is fed to it through wires 11 and 27, and the direct current power through wires 28 and 29 from the power supply 14, while the output of the amplifier is delivered through wires 15 and 16. As suitable values for all the circuit elements are suggested on the drawing, it is not necessary to go into further detail here.

The equation solved by the above described parallax corrector, namely:

$$p_\phi = \frac{57.3b \sin \phi g}{R \cos \theta g}$$

is based upon the assumption that R represents the "present range" R_p of the target. Actually the equation yields the correct values of p_ϕ only if R represents the "future range" of the target 75

(i. e., the range at the time of impact of the projectile). This future range R_f is given by the empirical relation:

$$R_f = R_p \left(1 + 1.2 \frac{dR}{dt} \right)$$

where

$$\frac{dR}{dt}$$

is the time rate of change of the range. A rotary motion proportional to the value of

$$\frac{dR}{dt}$$

15 is available in the range-repeater apparatus, as previously stated. The coefficient 1.2 in the above formula is empirical, and provides correction for the fact that usually the range of the target is decreasing, so that the parallax error angle increases more rapidly than would be accounted for by a unity coefficient.

The revised circuit, shown in Figure 3, enables the instrument to solve the modified equation:

$$p_\phi = \frac{57.3b \sin \phi g}{R_p \left(1 + 1.2 \frac{dR}{dt} \right) \cos \theta g}$$

Here the voltage from the wind box, proportional to $\cos \theta g$, is fed into terminals 34 and 35 of one 30 transformer 41 of a Scott transformer system in the range apparatus (10-to-1 step down) which has taps on the secondary winding 40 from which may be obtained the voltages desired. Across 35 taps 36 and 37 is placed a 10 ohm potentiometer 38 with a sliding contact 67 which is operated by the "range rate" shaft 39. The proper choice of voltage taps on the transformer yields a voltage as shown, proportional to

$$\left(1 + 1.2 \frac{dR}{dt} \right)$$

This voltage is fed across a 100 ohm potentiometer 42 with a sliding contact 68 actuated by the "present range" shaft 43, and as a consequence 45 we have across the conductors 44 and 45 a voltage proportional to

$$R_p \left(1 + 1.2 \frac{dR}{dt} \right)$$

50 This voltage is supplied from the range apparatus.

It is introduced into the parallax unit, shown to the right of the vertical dashed line, through 55 conductors 44 and 45 which feed it across a 1-to-1 isolating transformer 46. A 100 ohm balancing potentiometer 47 is provided between the two secondary windings 48 and 49 and the total secondary voltage is applied across a 2,000 ohm potentiometer 50 having a sliding contact 69 operated by the 36p_g shaft 51 of the computer. Thus the voltage across the tap on the balancing potentiometer 47 and the potentiometer 50 is proportional to:

$$p_\phi R_p \left(1 + 1.2 \frac{dR}{dt} \right) \cos \theta g$$

The voltage from the ϕg computer, proportional to $\sin \phi g$, is introduced into another transformer 70 52 of the Scott transformer system (10-to-1 step down) through conductors 53 and 54 as shown. The output of winding 55 of this transformer feeds into the parallax unit through another 1-to-1 isolating transformer 58 through conductors 56 and 57. Connected across the out-

put winding 59 of this transformer, is a resistance-capacitance circuit 73, 74, which combines a phase shifter and an amplitude control, including resistors 75 and 76. The contact 60 provides a means of shifting the phase of the $\sin \phi g$ voltage in order that it may be exactly 180° out of phase with the voltage across sliding contacts 61 and 69. The contact 62 on the 2,000 ohm potentiometer 70 provides means of making the voltage output of this net-work proportional to $b \sin \phi g$.

It will be seen that the circuits just described include a plurality of voltage dividers, namely, resistors 70, 73, 75 and 76 together with the sliding contacts movable thereover, and that all of these means jointly also constitute a voltage dividing means in the sense in which this term is used in the claim.

Two 5,000 ohm resistors 63 and 64 provide a voltage divider, the resistor 64 being connected across the input side of the amplifier 13. The amplifier design may be identical with that shown in Figure 2. Two other changes are embodied in the modified computer: first, a 5,000 ohm resistor 11 and a .5 mfd. capacitor 72 are placed in series with the input or field-energizing leads to the generator 22 to insure proper phasing of its output; second, the synchro-generator 24 of Fig. 1 turning through $12p_4$ is replaced by two differential synchro-generators, one 65 turning through p_4 , the other 66 through $36p_4$. The gear train is changed accordingly, the modified gear box 23a, through shaft 25b, causing the former $12p_4$ potentiometer, and the differential synchro-generator 66 now to turn instead through $36p_4$, and additionally through shaft 25a causing the differential synchro-generator 65 to turn through p_4 .

In this modified form the two differential synchro-generators 65 and 66 replace the synchro-generator 24 of the originally described form. Each of these differential synchro-generators receives an input through the set of three input conductors entering at its lower edge and yields an output through the corresponding set of three output conductors leaving at its upper edge. The inputs are derived from corresponding synchro-generators in the fire-control system, not shown, and the outputs lead to the gun director system, likewise not illustrated.

The remainder of the instrument is identical with that described previously.

The operation of the apparatus will be understood from its detailed description, but for convenience may be summarized as follows:

Referring first to the simpler form shown in Figs. 1 and 2, a signal proportional to $R \cos \theta g$ in amplitude, and having the input frequency determined by the power source, say 60 cycles per second, is introduced across the voltage divider 3 from the wind box. The generator 22 is also supplied with the same signal, as field excitation.

Tapped across the signal input conductors 1 and 2 are the two equal resistors 4 and 5 in series connection, whereby a "neutral" point between said conductors is established, to receive a second signal, namely the voltage difference existing between conductors 6 and 11, as determined by the position of slider 10 on resistor 9, the signal representing $\sin \phi g$, derived from the computer, being impressed across resistor 9.

Thus there exists in the amplifier input circuit the voltage between leads 11 and 26, from these two sources in series. However, there is also the voltage produced by generator 22. This voltage

is proportional, on the one hand, to the field excitation of the generator, which is derived from the same leads 1 and 2 that supply the voltage $R \cos \theta g$ to the voltage divider 3, and, on the other hand, is proportional to the rotational speed of the driving motor 17. The output voltage of this generator 22 is however opposed to the other two voltages in series therewith, and thus the input signal voltage supplied to the amplifier 13 is reduced thereby.

Through the gear box 23, the motor shaft 21 also operates the synchro-generator 24, and the arm 26 of the voltage divider 3, at a reduced speed, until a balance is attained, that is, until the voltage fed to the amplifier input terminals is reduced to zero. The voltage of the generator 22 assists in thus reducing the signal input voltage and thereby provides damping and prevents "hunting," or overshooting the zero position. The synchro-generator 24 yields the final output of the whole system, that is, the parallax-corrected gun order, which is supplied to the gun director system.

The operation of the Fig. 3 form is substantially the same as that of the one just described, with the exception that this system makes it possible to point the gun so that the missile will strike at the anticipated future position of a moving target. This is accomplished by means of the "range-rate" shaft 39 in cooperation with the "present-range" shaft 43, as already described. Due to the addition of shaft 39 and the potentiometer 38 controlled thereby, it becomes possible to provide a signal component representing a future value of the range and direction of the target, and to combine this with the other signals to produce the required pointing of the gun. The two differential synchro-generators 65, and 66 here supply the outputs of the device, which are fed to the gun director system.

Having disclosed the invention by describing a simplified form thereof, together with a preferred but more elaborate modification, it should be understood that this disclosure is provided solely for purposes of illustration and not as a limitation of the invention to all or any of the details thereof. The invention is defined solely in and by the following claim.

We claim:

50. In a parallax corrector for a gun, means for electrically producing an alternating voltage representative of the cosine of the elevation angle of the gun, a resistor having a sliding contact movable thereover, connections from said means to the terminals of said resistor to maintain across said resistor a voltage representative of the cosine of said elevation angle, rate responsive means connected to said contact for generating an alternating voltage that is a function of the range rate of the target, mechanical connections whereby said rate responsive means moves said contact over the resistor, a second resistor having one terminal electrically connected to said contact and having its other terminal electrically connected to a fixed point of said elevation voltage producing means, said second resistor having a sliding contact movable thereover, range responsive means mechanically moving said last named contact in accordance with the range of the target thus providing a modified alternating voltage proportional to the product of the range, a function of range rate and the cosine of the angle of elevation, means for electrically producing an alternating voltage representative of the sine of 55 the train angle of the gun, voltage dividing means

electrically connected to combine said modified voltage with a predetermined portion of said train angle voltage, thus producing a control voltage that is proportional to the product of the range, a function of range rate and the cosine of the angle of elevation, a potentiometer across which said control voltage is applied, an amplifier for said control voltage, and servo mechanism controlled by the output of said amplifier and including a motor and a generator operated thereby, for adjusting said potentiometer and for generating a voltage representative of the parallax correction.
